MULTITONE WHISTLE

William R. Smith, Philadelphia, Pa., assignor to
The A. C. Gilbert Company, New Haven, Conn.,
a corporation of Maryland

Application May 14, 1949, Serial No. 93,380

9 Claims. (Cl. 116—137)

1

This invention relates to whistles and particularly to multi-toned whistles of miniature size for incorporation in the extremely limited spaces available in the smallest gauges of toy railway trains or rolling stock, and in tiny trackside toy buildings.

It has been proposed to provide multi-toned whistles operated by split streams of air generated by the same motor-driven air impeller, but the problem of condensing into a much more tiny space than heretofore a resonance chamber having sufficient air volume to produce deep and low-pitched tones such as will effectively imitate the actual noise of a distant train whistle, has presented problems more acute than those of reducing the size of the air impeller and its motor which generate the sound producing streams of air. Heretofore production of plural whistle tones has been accomplished by making one resonance chamber greater in straight length than a companion resonance chamber. This has required a greater maximum overall dimension of the sound box than has been available in toy trains of the very miniature sizes such as the so-called "HO" gauge.

It is an object of this invention to provide a miniature whistle of satisfactorily loud and low pitched tone having at least one, and preferably a plurality of, resonance compartments of such construction, shape and relationship that the aggregate size of a chamber divided into such plural compartments may be compacted into overall proportions whose maximum dimension in the direction of its greatest length is smaller than has heretofore been possible.

A related object is to differentiate the tone and pitch produced by companion resonance compartments by variation in the width, rather than in the length, of the compartments.

Another object is to produce a resonance chamber of effective elongation in tortuous form without the use of tubing structure.

Still another object is to integrate plural resonance chambers into a comparted sound box having the above characteristics constructed substantially throughout of substantially flat walls and partitions thereby to facilitate its casting from metal.

Means for attaining the above and related objectives of the invention will appear in the following description of a successful embodiment thereof, which description has reference to the appended drawings wherein:

Fig. 1 is a side view of a motor-driven rotary air impeller mechanically associated with a mini-

2

ature sound box embodying the present invention and drawn on a considerably larger scale than the preferred actual size, portions thereof being broken away or shown in section on a central vertical plane to expose the construction.

Fig. 2 is an isometric view of the sound box drawn on a still larger scale with some of its exterior walls and interior partitions removed or partially broken away better to reveal the construction.

Fig. 3 is a fragmentary view of a portion of the structure shown in Fig. 2 with certain walls and webs of the sound box still further broken away to exhibit certain features of the air flow.

15 Figs. 4, 5, 6, and 7 are, respectively, views taken in section on the planes 4—4, 5—5, 6—6, and 7—7, in Fig. 1, looking in the direction of the arrows.

In Figs. 1 and 4 my improved sound box designated 12 as a whole is shown removably assembled to and supported solely on a frame bracket 13 which may be integral with or a rigid part of the body of a toy railway locomotive or other hollow piece of rolling stock (not shown) or contained 20 in toy building structure such as a tiny track-side power plant in whose restricted space limits the sound box must be contained and concealed. Also rigid with frame bracket 13 is a bearing bracket 14 in which is journaled one end of the shaft 15 of a motor 16, the other end of shaft 15 being journaled in a bearing cup 19 lodged in upright wall 25 of the sound box 12, which cup is coaxial with the shaft bearing in bracket 14. Motor shaft 15 carries an air impeller 20 fixed thereon by press fit over the knurled shaft portion 21 for rapid rotation in the blower cavity 22. Cavity 22 as best shown in Fig. 4 is of snail shape and is bordered by the upright wall 25 of the sound box.

Sound box 12 may be cast of metal in a shape to have the top wall 26, the end wall 27 and bottom wall 28, all integral and continuous with one another and with the upright wall 25. The remaining walls 31 which surround blower cavity 22 may also be integral or continuous with upright wall 25 and are provided with threaded holes 32 receiving the screws 33 which fasten the sound box 12 to bearing bracket 13 in a manner to derive its sole support from the latter. Other threaded holes 34 in the sound box casting receive screws 35 which serve to fasten side plates 36 against the sides of the sound box in a manner to make a pneumatically tight joint therebetween, thus completing the inclosure for the hollow interior of the sound box.

According to the present invention, and for the purpose of producing a sound box of sufficient volumetric capacity to afford effective resonance and whose maximum dimension in the direction of its greatest length shall be smaller than has heretofore been possible, the interior of the sound chamber closure is comparted by a system of partitions and/or web walls shaped and arranged to attain the indicated novel result. There is an upright partition wall 40 shaped and arranged in the sound chamber space to divide the latter into side-by-side separated resonance compartments 41 and 42, so that the former is wider than the latter. In resonance compartment 41 there are two mainly flat web walls 43 and 44 in spaced planes. In resonance compartment 42 there are two similar web walls 45 and 46 substantially co-planar with walls 43 and 44, respectively. The web walls on a common side of partition wall 40 have free edges 47 spaced from respectively opposite walls 25 and 27 of the sound chamber closure. Thus each of the resonance compartments is converted to a tortuous shape. Some of the advantages of this invention might be obtained if only one web wall were to be incorporated internally of one or both of the resonance chambers. One such web wall could serve to convert at least a portion of the interior of the resonance chamber to the shape of a return bend.

By any or all of the expedients above disclosed there is produced a greater tone deepening effective length of resonance chamber giving a more satisfactory amplification of sound realistically like the whistle of a distant train or industrial plant than would otherwise be possible in a sound box having equally small dimensions. The dimensions possible in the present instance may be as tiny as a cubic inch or smaller.

The stream of air generated by the impeller 20 in blower cavity 22 is forced through an entrance orifice 49 in the box wall 25 into a laterally extending distributing channel 50 from which it seeks to escape in the direction of the arrows in Fig. 3 through separate tapering blow orifices 51 and 52 toward the separate bodies of air trapped in both resonance chambers 41 and 42. The former gives from channel 50 toward the relatively wider resonance compartment 41 while the latter gives from the same channel toward the relatively narrower resonance compartment 42. Directly adjacent the elongated blow orifices 51 and 52 respectively there are correspondingly elongated outlets 53 and 54 in base wall 28 constructed and located to afford outlet for the separate streams of air passing through blow orifices 51 and 52 to the exterior of the sound box. Such streams of air are in reactive fluid communication with the resonating air confined in compartments 41 and 42. As is well known in whistle construction, the edge 55 of each of the outlets 53 and 54 is preferably sharpened to a wedge shape in order to cleave and vibrate the outflowing streams of air. As will be clear from Figs. 5 and 6, blow orifices 51 and 52, as well as the outlets 53 and 54, are pneumatically isolated from each other by the intervening partition wall 40.

It has been found that the resonating action of the body of air trapped in compartments 41 and 42 is improved in distant train whistle imitating effect if generous fillets are provided at the interior corners formed by the wall and/or partition junctions which define the tortuous length of the compartments as indicated at 56 in Figs. 1 and 2. It is assumed that this reduces eddy cur-

rents and gives more freedom to the wave surges of the resonance action.

Having thus described but one illustrative embodiment of these new principles in multi-tone sound box construction wherein a difference in tone is produced by difference in the lateral cross-sectional size, rather than the tortuous length, of plural cooperative resonance compartments, the appended claims are directed to and intended to cover all variations and substitutes for the particular parts, shapes and arrangements herein pictured and described as come within the most inclusive fair means of their definitions.

I claim:

1. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, and a partition wall in said chamber space shaped and arranged to divide the latter into pneumatically separate air-resonating compartments of respectively differing volumetric capacity, at least one of said compartments having a tortuous shape whereby relatively long and narrow proportions are imparted thereto for producing whistle noises of lower tone.
2. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, a partition wall in said chamber space shaped and arranged to divide the latter into pneumatically separate air-resonating compartments of respectively differing volumetric capacity and substantially similar tortuous shapes having similar effective resonating lengths, said partition wall being situated to cause said compartments to differ in width sufficiently to cause a difference in pitch of the whistle tones produced thereby.

3. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, a partition wall in said chamber space shaped and arranged to divide the latter into pneumatically separate air-resonating compartments of respectively differing volumetric

capacity, and at least one web wall inside of at least one of said compartments shaped and arranged to convert at least a portion of the compartment into a tortuous shape having a return bend whereby relatively long and narrow proportions are imparted to the compartment for producing whistle tones of lowered pitch.

4. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, a partition wall in said chamber space shaped and arranged to divide the latter into pneumatically separate air-resonating compartments of respectively differing volumetric capacity, and web walls inside of said compartments in coplanar alignment while located on respectively opposite sides of said partition wall, said web walls being shaped and arranged to convert each of said compartments into a tortuous shape whereby relatively long and narrow proportions are imparted thereto for producing whistle tones of lowered pitch.

5. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, a partition wall in said chamber space shaped and arranged to divide the latter into pneumatically separate air-resonating compartments of respectively differing volumetric capacity, and a plurality of web walls inside of at least one of said compartments shaped and arranged to convert the compartment into a tortuous shape imparting relatively long and narrow proportions thereto for producing whistle tones of lowered pitch.

6. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, a partition wall in said chamber space shaped and arranged to divide the latter into pneumatically separate air-resonating compartments of respectively differing volumetric capacity, and a plurality of web walls inside of at least one of said compartments located in spaced planes each having a free edge spaced from respectively opposite walls of said closure in a manner to convert the compartment into a tortuous shape imparting relatively long and

narrow proportions thereto for producing whistle tones of lowered pitch.

7. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, a partition wall in said chamber space shaped and arranged to divide the latter into pneumatically separate air-resonating compartments of respectively differing volumetric capacity, and a plurality of mainly flat web walls inside of at least one of said compartments located in spaced planes each having a free edge spaced from respectively opposite walls of said closure in a manner to convert the compartment into a tortuous shape imparting relatively long and narrow proportions thereto for producing whistle tones of lowered pitch.

8. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, a partition wall in said chamber space shaped and arranged to divide the latter into pneumatically separate air-resonating compartments of respectively differing volumetric capacity, and a plurality of mainly flat web walls on each side of and joined to said partition wall, the web walls on opposite sides of said partition wall being in substantially planar alignment and the web walls on each common side of said partition wall being located in spaced planes thereby to convert the compartments into tortuous shapes imparting relatively long and narrow proportions thereto for producing whistle tones of lowered pitch.

9. In a whistle for containment within the tiny interior of miniature hollow toys, a comparted multi-tone sound chamber comprising in combination, walls forming a box-like closure confining a chamber space for trapping a volume of resonating air, at least one blow orifice shaped and disposed to direct a stream of whistle-producing air toward and into fluid communication with said space-trapped volume of air, at least one air outlet in one of said closure walls close to said blow orifice shaped and disposed to permit said stream of air to escape to the exterior of said chamber space, a partition wall in said chamber space shaped and arranged to divide the latter into pneumatically separate air-resonating compartments of respectively differing volumetric capacity, and a plurality of mainly flat web walls on each side of and joined to said partition wall, the web walls on opposite sides of said partition wall being in substantially planar alignment and the web walls in each common side of said partition wall being located in spaced planes, each of the last said web walls having a

free edge spaced from a wall of said closure in a manner to convert each of said compartments into a tortuous shape imparting relatively long and narrow proportions thereto for producing whistle tones of lowered pitch.
